UNITED STATES PATENT OFFICE.

THOMAS P. ASBURY, OF TINGLEY, IOWA.

WEATHER-STRIP.

SPECIFICATION forming part of Letters Patent No. 376,846, dated January 24, 1888.

Application filed July 28, 1887. Serial No. 245,515. (No model.)

To all whom it may concern:

Be it known that I, THOMAS P. ASBURY, a citizen of the United States, residing at Tingley, in the county of Ringgold and State of Iowa, have invented certain new and useful Improvements in Weather-Strips for Doors or Windows, of which the following is a specification, reference being had therein to the accompanying drawings.

This invention relates to certain new and useful improvements in weather-strips for doors; and the object of the invention is to provide a weather-strip which shall effectually prevent the entering of driving rain, and yet at the same time to so construct the strip that the same can be readily taken up and removed when there is no sign of a storm.

I am aware that weather-strips have been heretofore constructed so as to be permanently attached to the lower edge of the door; but in many instances, especially in summer weather, there are sometimes long periods during which it rains only occasionally, and when such is the case it is very desirable to have a strip capable of being removed from the door and put away until such time as needed, when in a few moments it can be replaced. In my invention I have endeavored to accomplish these ends and to also provide a strip whose construction is simple and inexpensive and not liable to get out of order.

In the accompanying drawings, forming a part of this specification, and on which similar letters of reference indicate the same or corresponding features, Figure 1 represents a perspective view of a door and door-frame, showing my improved strip attached and the door in the act of being opened. Fig. 2 is a perspective view showing the door shut. Fig. 3 is a vertical cross-sectional view through the door and frame, taken on the line $y-y$ of Fig. 1, the door being shut. Fig. 4 is a detail view of the holding-plate attached to the sides of the weather-strips. Fig. 5 is a detail plan view showing the weather-strip, the water-proof material, and the holding-plate.

The letter A designates the frame-work of a door, of the usual or any approved construction, the same consisting of uprights, one at either side, and transverse connecting-beams, one at the top and the other at the bottom, the latter one in this instance being provided with

a sill, B, flush with the bottom of the door when the same is shut, and slanting in both directions therefrom. The side frame at its lower end, at a point where it comes in contact with the door, is cut away for a portion of its length, and over said cut-away or recesses is secured by nails or otherwise a metallic plate, C, as more clearly seen in Fig. 3, the object of which is to keep in place the flexible water-proof material, D. This water-proof material, D, may be made entirely of rubber or of cloth covered with rubber, the latter preferred on account of its flexibility, and it extends beyond the door on the outside and is made somewhat wider than the frame on its sides, so that the said sides or edges may be upturned and inserted in the plate E, which is held in place by the metallic plate C, and on the inside of the door said water-proof material is secured to the strip H and held thereby means of the plate I.

Each end of the weather-strip is provided at that point where the door closes upon the same with a holding-plate, E, as clearly seen in Fig. 4, the water-proof material being laid therein and the plate clamped upon it, the lug F of which is clearly seen projecting under the key G in Fig. 1.

The left-hand side of the plate shown in the drawings (the same being the one which goes on the left-hand side of the door) is provided with a projecting lug, F, which is engaged or rather over which fits the key G, (shown in Fig. 1,) thus fastening the plate and strip in place. On the other side of the door-frame a similar plate, E, having a projection, F, is provided for the same purpose. When it is desired to remove the weather-strip, this key G is turned so that it will not engage with the plate, and the latter can then be withdrawn.

Pivotedly mounted by means of staples L and pivot-pins K across the lower edge of the door-frame on the inside is a strip, H, the same being covered with sheet metal I, save near each end, where said sheet metal is cut away. The water-proof material, D, above described, is held in place against this strip H by means of the said sheet-metal plate I, and, being somewhat longer than the plate, its ends J extend beyond the point where said plate is cut away, and its extended ends are inserted between the edges of the plate E, and said plate E is then pushed

or inserted between the plate C and the side pieces forming the door-frame, so as to hold the said water-proof material in proper position. The ends J' of the water-proof material 5 projecting above the hinged sill are held on the one end by the plate E, and when the door is shut the free ends are pressed up closely around the edge of the door and prevent the entering of any water which might possibly 10 come through between the door and door-frame.

The frame as shown in this instance is provided with a hook or stud, M, over which extends one end of a spiral spring, N, the other 15 end being attached to the beam J. The object of this spring is to hold the strip up in an inclined position against the door when the same is shut, as shown in Fig. 2, and yet the spring is made sufficiently elastic to permit of its being 20 easily opened, at which time the door depresses the otherwise held-up beam J and readily passes over it. The jamb or side beams of the door on the outside are provided with studs O on either side, beneath which fits a 25 bar, P, the same being used for the purpose of firmly holding down the water-proof material, D, so that the wind will not be able to upset its outer end and allow the rain to get under it, and thus beat into the house.

30 It is to be observed that I may, if it be found desirable, provide each end of the strip H with a spring, N, and I have shown only one in this instance, as one will do the work on an ordinary-sized door.

35 Having thus fully described my invention, what I claim as new, and desire to secure by Letters Patent, is—

1. The combination, with the door and the frame-work thereof, formed on its opposite 40 lower inner edges with recesses, of a weather-strip having holding-plates which are flexibly connected to the strip and fitted in said recesses, and a spring to elevate the strip.

2. The combination, with a door and the frame-work thereof, formed on its lower ends 45 with recesses, of a weather-strip having a sheet of flexible water-proof material attached thereto, and holding-plates at either end of the sheet which fit in said recesses, and a spring 50 to elevate the strip.

3. The combination, with the door and the frame-work thereof, having a sill slanting in

both directions and studs on the outside, of flexible water-proof material extending between the door and the sill and held on the outside in a flat position by a longitudinal bar fitting under the studs and fastened on the inside to the weather-strip, and having holding-plates which fit into the side frames of the door.

4. The combination, with the door and the frame-work thereof, formed on its lower inner ends with recesses and provided with turning-keys, of a weather-strip having holding-plates which are flexibly connected to the strip and 60 fit in the said recesses and are securely held by the keys, and a spring attached to the frame-work and the strip and adapted to elevate the latter when the door is shut.

5. The combination, with a door and the frame-work thereof, formed on its lower ends with recesses and provided with a turning-key, of a weather-strip having a flexible water-proof sheet attached thereto and holding-plates at either end of the sheet which fit in 75 the said recesses and are securely held by the keys, and a spring attached to the frame-work and the strip and adapted to elevate the latter when the door is shut.

6. The combination, with a door and the frame-work thereof, having staples on either side of the door, of a strip having a sheet of flexible material attached thereto and pivot-pins fitting within the staples, and a spring attached to the frame-work and the strip, so 85 as to elevate the latter when the door is shut.

7. The combination, with the door and the frame-work thereof, having staples on either side of the door and having the lower inner ends of the jambs formed with recesses, of a 90 weather strip having pivot-pins fitting within the staples and a sheet of flexible water-proof material attached thereto, provided with holding-plates which fit within the recesses of the jambs, and a spring attached to the frame-work and the strip to elevate the latter when the door is shut.

In testimony whereof I affix my signature in presence of two witnesses.

THOMAS P. ASBURY.
